UNITED STATES PATENT OFFICE.

WEIMER G. SANDS, OF READING, PENNSYLVANIA.

FOLDING AND RECLINING CHAIR.

SPECIFICATION forming part of Letters Patent No. 268,941, dated December 12, 1882.

Application filed August 11, 1882. (Model.)

To all whom it may concern:

Be it known that I, WEIMER G. SANDS, of Reading, in the county of Berks and State of Pennsylvania, have invented certain Improvements in Folding and Reclining Chairs, of which the following is a specification.

My invention relates to folding and reclining chairs; and it consists in various features and details, hereinafter fully set forth.

10 In the accompanying drawings, Figure 1 is a side elevation of the chair with the back in an upright position and the foot-rest thrown down out of position for use. Fig. 2 is a similar side view, showing the back inclined and the foot-rest elevated to form a reclining-chair; Fig. 3, a view illustrating the manner of folding the chair; Fig. 4, a view of the chair folded for storage or shipment.

20 The object of my invention is to furnish a simple and cheap chair which may be adjusted by the occupant to and held at any desired inclination by merely bearing against the foot-board or the back without rising from the chair or materially altering his position, and which may also be folded into compact shape for 25 shipment or storage. To accomplish this object I construct my improved chair as shown in the drawings, in which—

30 A B represent the legs crossed and pivoted, and in all respects resembling the legs of the common camp-stool, except that the front legs, A, are made to extend higher than the back legs, B, and are formed with a slot, a, as shown in Figs. 1 and 2.

35 C represents the back, which is sustained by pivot-pins or journals b, extending through the slots a of the front legs; and D indicates the seat-frame, which is jointed at its rear to the lower end of the back frame, at some distance 40 below the pivots b, and is sustained at its front by a rod, c, connecting the upper forward ends of the rear legs, B, and passing through slots d in the side rails of the seat-frame. The rod c thus serves, in connection with rounds or cross-rails e, to connect the two sides of the supporting-frame of the chair, besides sustaining 45 the front of the seat.

E represents a jointed brace or link extending from the upper end of the leg B to a point 50 at about the same height, or a little above, on the leg A, said brace serving to limit the separation of the legs A B, and by reason of the

joint f permitting the two sections of the brace to rise and fold together when the chair is folded.

55 F represents one of the arms of the chair, which is supported about midway between its ends by an ear, g, pivoted upon the same bolt or pin f which forms the pivot or joint of brace E. The arms rest at their rear ends upon the 60 legs A, and to their forward ends are hung or jointed by joints or pivots h the side bars or irons, i, of a foot-rest, G, which irons are likewise pivoted or jointed to the sides of the seat-frame D, near its forward edge, as shown at j. 65 The pivots i form the center of motion of the foot-rest, about which it swings up or down; and as said rest is connected with the seat D below these pivots, and as the seat is arranged to slide upon the rod c when actuated by the 70 pivoted or rocking back, to which it is jointed, it will be seen that as the back is thrown toward a horizontal position the seat will be slid forward upon the rod and the foot-rest will be swung upward about its pivot i. When, on 75 the other hand, the back is raised or caused to stand upright the seat will slide backward and draw down the foot-rest. The occupant of the chair can therefore, by resting his weight mainly upon the seat D, and pressing with his 80 back against the back C, throw the same downward and produce a reclining chair or cot, sufficient pressure only being applied by the legs to the foot-rest to prevent the too sudden fall of the back. If it be desired to raise the back 85 and depress the foot-board, it is merely necessary to withdraw the pressure from the back and apply it to the foot-board.

90 It is important that the slots d be not long enough to permit the back to assume a horizontal position or to come in line with the seat when the pivots are at the bottom of slots a, as in that case the upper end would fall to the ground. I therefore make the slots of such length that the joint or pivot connecting the 95 back and seat shall always stand below a line passing through journals or pivots b and rod c when said pivots b are resting in the lower ends of slots a. When, however, it is desired to fold the chair the journals or pins b are raised 100 to the top of slots a, which allows the pivots or joints connecting the seat and back to come into line with the journals b and rod c, and to swing upward above them, as indicated in Fig.

3, allowing the chair to be folded, as in Fig. 4.
Having thus described my invention, what I
claim is—

1. In combination with the legs A B, the for-
mer having slots *a*, the back C, pivoted in said
slots and connected at its lower extremity with
the seat, substantially as set forth, whereby
the pivots of the back may be raised and the
back turned over against the legs, substan-
tially as explained.

2. In combination with the legs A B and a
seat supported thereby, jointed braces E, inde-
pendent of the seat, connecting the legs, as
shown, whereby the legs are permitted to fold
together, but are prevented from spreading too
far apart.

3. In combination with the crossed legs A B,
jointed braces E, connecting the legs above
the point of crossing, and a seat, arms F, piv-
oted to the braces at the joint *f* of the latter,

whereby the arms are caused to fold closely
against the chair-frame when the latter is folded.

4. In combination with crossed legs A B,
braces E, and arms F, the seat D, jointed to
the pivoted back C, and the foot-rest G, sus-
pended from the arms F and jointed or pivoted
to the seat, substantially as shown and de-
scribed.

5. The herein-described chair, consisting of
legs A B, connected by braces E, and the for-
mer having slots *a*, arms F, pivoted to the
braces E, foot-rest G, suspended from arms F,
sliding seat D, jointed or pivoted to foot-rest
G, and back C, pivoted in slots *a*, and connect-
ed with the seat, substantially as shown and 35
described.
